UNITED STATES PATENT OFFICE

EARLY G. THOMPSON, OF BREWTON, ALABAMA, ASSIGNOR OF FORTY-NINE ONE-HUNDREDTHS TO E. M. BLACKSHER, OF BREWTON, ALABAMA

ROLLER SKATE

Application filed September 15, 1930. Serial No. 482,095.

The invention relates to roller skates and has for its object to provide a device of this character, particularly adapted for long distance skating, and provided with an upwardly extending brace member terminating in a body engaging plate and provided with spring means for normally imparting an upward lift on the skates, thereby assisting the wearer in lifting the skate during the skating operation.

A further object is to provide the skate with an upwardly extending arm pivoted thereto, which arm is slidably connected to a second arm adapted to be anchored to the body of the operator and provided with spring means for assisting in lifting the skate during a skating operation.

A further object is to slidably mount the lifting and bracing arm in a tubular member and to provide an expansion spring in the tubular member and cooperating with the lifting arm for normally forcing the same upwardly.

A further object is to provide an expansion spring in the tubular member which lifts the skate upwardly and also pulls down on the shoulder of the operator which keeps the operator's body balanced on the skates during operation of same at all times. This is very important to inexperienced operators which keeps them from getting overbalanced while learning to skate.

A further object is to pivot the upper end of the tubular arm section to an arcuate plate adapted to engage the hip of an operator and provided with means for circling the waist of the operator, and with an upwardly extending flexible member adapted to extend over the shoulder of the operator for suspending the weight of the skate from the shoulder of the operator.

A further object is to provide the lifting and brace arm with means whereby a spare wheel may be carried thereby for use in distance skating.

With the above and other objects in view the invention resides in the combination and arrangement of parts as hereinafter set forth, shown in the drawings, described and claimed, it being understood that changes in

the precise embodiment of the invention may be made within the scope of what is claimed without departing from the spirit of the invention.

In the drawings: 53

Figure 1 is a front elevation of the skate showing the same applied.

Figure 2 is an inner side elevation of one of the skates.

Figure 3 is a vertical transverse sectional view through the lower end of the tubular member. 60

Figure 4 is a top plan view of one of the skates.

Figure 5 is a detail perspective view of 65 the rear arm of the front truck of one of the skates.

Referring to the drawings, the numeral 1 designates the body of the skate which is preferably formed from metal stamped to 70 form a heel receiving portion 2 and a toe receiving portion 3. Extending downwardly from the body 1 is a rear truck 4 and a forward truck 5 which carry wheels 6, preferably provided with pneumatic tires 7. The 75 rear truck extends the axle of rear wheel back of the heel of the operator, so the weight of the operator's body will be equally divided between the rear axle and the forward axle. The forward truck is pivotally connected at 8 80 to the forward end of the body, and has its rear arm 9 provided with a transverse portion 10 having a ball bearing groove 11 for the reception of a ball bearing 13 so that the truck will have a slight transverse pivotal 85 action for cutting during a skating operation. Transverse portion 10 is provided with a slot 14, for pin 12 which extends downwardly through an arcuate slot 14 for limiting the pivotal action of the forward truck 90 5. The body 1 is provided with straps 15 whereby the same may be securely attached to the shoe of the operator.

Extending upwardly from the outer side of the skate body 1 is an ear 16, to which 95 is pivotally connected at 17 the upwardly extending brace arm 18. Brace arm 18 is preferably formed from rod material and extends into the lower end of the anchored tubular arm section 19 through the threaded cap 20 car- 100

ried by the arm section 19. Secured to the upper end of the brace rod section 18 is a head 21 which is slidably mounted on the section 19, and interposed between the head 21 and the threaded cap 20 is an expansion spring 22, which exerts an upward pull on the brace rod 18, and assists in lifting the skate during a skating operation.

The above action relieves the weight on the feet of the operator, and also exerts a downward pull on the shoulder of the operator, which helps keep the operator's body balanced on the skates, which is a decided advantage in long distance skating, for which the device is particularly adapted. Head 21 is threaded at 23 on the arm section 18.

By adjusting the member 21 on the rod 18, it is obvious that the amount of expansive power exerted on the member 21 may be varied, thereby the amount of power applied to the lifting action on the skate may be adjusted. Cap 20 is preferably provided with apertures 24 through which air may escape for allowing freedom of movement of the member 21. The rod 18 is preferably provided with a lock nut 25 for locking the member 21 against rotation.

The upper end of the tubular section 19 of the brace arm is pivotally connected at 26 to an arcuate plate 27, which is adapted to engage the hip 28 of the operator, and is provided with straps 29 which connect around the waist of the operator for holding the brace arms adjacent the legs of the operator during a skating operation. It will be noted that the arm 18 may pivot forwardly and rearwardly in relation to the skate body 1; it will also be noted that the arm 18 will twist freely to the right or left when the operator twists his foot, but not transversely, therefore it will be seen that the skate is thoroughly braced and the strain on the ankle of the operator is relieved. Connected to the upper side of the plate 27 is a strap 30, which arches the shoulder 31 of the operator, thereby suspending the weight of the entire device from the shoulders allowing freedom of use of the arms and relieving strain on the legs.

In long distance skating it is desired to provide means for carrying a spare wheel, and to accomplish this result the tubular member 19 is provided with a shaft 31 for the reception of the spare wheel 6a, and pivotally connected at 32 to the tubular section 19 is an arm 33, the lower end of which is provided with a bifurcation 34, which receives the outer end 35 of the shaft 31, and on which a retaining nut 36 is threaded.

From the above it will be seen that means is provided in connection with a roller skate whereby the weight of the skate is suspended from the shoulder of the operator, means provided for lifting the skate during the skating operation, partially or in whole, and

means is provided for preventing side tilting of the skate, thereby relieving the strain on the ankle of the operator. A skate of this character is provided for long distance skating. It will also be seen that means is provided to help balance the operator while learning to stand up on the skates, making this skate superior to any other skate made. A new operator will not have to take so many falls when learning to skate.

The invention have been set forth what is claimed as new and useful is:

1. The combination with a roller skate, of a brace arm pivotally connected thereto and extending upwardly at the side of a leg of the operator, a plate to which said arm is pivotally connected, means for attaching said plate to the hip of the operator and means connecting said plate and the shoulder of the operator whereby the weight thereof is supported.

2. The combination with a roller skate, of a brace arm pivotally connected to the side of said skate, means for anchoring the upper end of said brace arm to the body of the operator, said brace arm being formed from slidably connected sections, and spring means cooperating with said slidably connected sections whereby an upward lifting force is applied to the skate.

3. The combination with a roller skate, of a brace and lifting arm carried thereby, said arm comprising a section hingedly connected to the skate, a second section in which the first mentioned section is slidably disposed, an adjustable head carried by the first mentioned section within the tubular section, a cap threaded on the lower end of the tubular section and an expansion spring interposed between the adjustable head and cap and forming means whereby a lifting force is applied on the arm section connected to the skate and means whereby the upper end of the tubular section may be anchored to the body of the operator.

4. The combination with a skate, of a brace and lifting arm carried thereby and extending upwardly, said brace and lifting arm being formed from telescopically engaged sections, spring means cooperating with the telescopically engaged sections whereby the section connected to the skate is forced upwardly, means for anchoring the upper end of the arm to the body, and means for suspending said last named means from the shoulder of the operator.

In testimony whereof he hereunto affixes his signature.

EARLY G. THOMPSON.
